UNITED STATES PATENT OFFICE.

EMANUEL M. GEIGLE, OF BALDWIN, NORTH DAKOTA.

CATTLE POKE.

1,411,081.

Specification of Letters Patent. Patented Mar. 28, 1922.

Application filed May 24, 1921. Serial No. 472,104.

To all whom it may concern:

Be it known that EMANUEL M. GEIGLE, a citizen of the United States of America, residing at Baldwin, in the county of Burleigh 5 and State of North Dakota, has invented new and useful Improvements in Cattle Pokes, of which the following is a specification.

The object of the invention is to provide 10 a simple and efficient means for preventing cattle from goring or injuriously attacking fences, particularly wire fences such as are now commonly employed as the means of enclosing pastures; and furthermore to provide 15 a device for the purpose indicated which can readily and quickly be applied to the animal and which will not restrain or afford any inconvenience to the cattle in grazing or otherwise except in the event that 20 the animal should attempt to force its way through a fence or similar enclosing means; and with these objects in view the invention consists in a construction and combination of 25 parts of which a preferred embodiment is shown in the accompanying drawings, wherein:

Figure 1 is a general view of a device embodying the invention applied in the operative position to an animal.

Figure 2 is a plan view of the same.

Figure 3 is a section on the line 3—3 of Figure 2.

Figure 4 is a perspective view of the clamp.

The device consists essentially of a saddle 35 10 preferably made of relatively light metal adapted to straddle and rest upon the back of the neck of the animal as indicated in Figure 1 and carrying a clamp 11 for engaging the hide at the back of the neck, and 40 an upwardly directed poke frame adapted to engage with the wires or strands of a fence when the animal makes an effort to pass through or gore the fence in an effort to escape from the pasture or enclosure.

In the construction illustrated the clamp 45 is provided with divergent arms 13 connected by a spring coil 14 having inwardly directed terminal spurs 15 for engagement with the loose hide at the neck of the animal 50 and which can be so engaged without ap-

preciable inconvenience or distress to the animal except when, strain being applied to the saddle tending to pull the clamp away from the neck, the animal is aware of a pricking or pulling sensation which serves to 55 act as a restraining influence and causes it to desist from the efforts which have resulted in such sensation.

The clamp is secured to the saddle by means of a pin 16 fitted terminally in seats 17 in spanning relation with an opening 18 in the saddle, said pin being provided with a finger hold 19 so that after the clamp has been positioned in engagement with the hide at the neck of the animal the saddle may be 60 placed thereover and the pin inserted through the ring or coil of the clamp to lock 65 the saddle in its proper position.

The upstanding poke frame consists of uprights 20 connected by a cross bar 21 and 70 downwardly and rearwardly inclined braces 22 which serve to give solidity to the structure, and when the animal wearing the device attempts to pass through a fence the contact of a runner or strand of the fence 75 wire with the uprights tends to tilt the saddle rearwardly or raise the front end thereof and thus apply a strain to the clamp which as above indicated causes sufficient inconvenience to the animal to result in inducing it to desist.

Having described the invention, what is claimed as new and useful is:—

1. A cattle poke having a saddle carrying a depending clamp for engaging the hide at 85 the back of the neck of the animal and an upstanding poke frame for contact with a fence strand or runner, the saddle being provided with an opening spanned by a removable pin engaging the clamp for connecting 90 the same to the saddle.

2. A cattle poke having a saddle carrying a depending clamp for engaging the hide at 95 the back of the neck of the animal and an upstanding poke frame for contact with a fence strand or runner, the said frame consisting of uprights connected by a transverse rod and braces extending rearwardly and downwardly from the upper ends of the uprights, whereby rearward pressure upon the 100

uprights serves to cause a tilting action of the saddle.

3. A cattle poke having a saddle and a clamp depending therefrom for engaging the hide at the back of the neck of the animal, and an upstanding poke frame mounted on the saddle for contact with a fence strand

or runner, the saddle being detachably secured to the clamp for attachment thereto after the latter has been engaged with the 10 hide.

In testimony whereof he affixes his signature.

EMANUEL M. GEIGLE.
